UNITED STATES PATENT OFFICE.

HERBERT FORESTER, OF CLEVELAND, OHIO, ASSIGNOR OF ONE-HALF TO ALEXANDER M. SKIBINSKY.

LIQUID-FUEL BURNER.

1,285,099.

Specification of Letters Patent. Patented Nov. 19, 1918.

Application filed November 27, 1917. Serial No. 204,141.

To all whom it may concern:

Be it known that I, HERBERT FORESTER, a subject of Great Britain, residing at Cleveland, in the county of Cuyahoga and State of Ohio, have invented certain new and useful Improvements in Liquid-Fuel Burners, of which the following is a specification. This invention relates to liquid fuel burners for heating furnaces, boilers, brick and pottery kilns, and similar purposes.

The main object of the invention is to provide a burner, which is economical in the use of liquid fuel such as kerosene or crude oil, and will generate gas from the same flowing to the burner by gravity so as to produce a blue flame without the need of air pressure.

Another object of the invention is to provide a burner of said character of simple and inexpensive construction, which is easy to clean without detaching it from the furnace or other places where installed.

In order that the invention may be clearly understood, the same will be hereinafter fully described as illustrated in the accompanying drawings, showing a preferred embodiment thereof, and its novel features will be distinctly pointed out in the appended claims.

Figure 1 is a longitudinal section of a burner constructed in accordance with my invention,

Fig. 2 is a front end view of the same,

Fig. 3 is a sectional view taken on line 3—3 of Fig. 1, and

Fig. 4 is a plan view of the elongated semi-cylindrical chamber.

Referring to the drawings, 1 represents an elongated semi-cylindrical casing having its flat side 2 forming the top. Said top is preferably constructed of pottery and is perforated by two rows of suitable transverse slots 3, separated by a wall 4. The open ends of said casing are closed by a pair of plates 5 and 6, which are held in place by tie-bolts 7 passing longitudinally through the casing. The front end plate 6 is provided with an opening 8, in which is fixed a tubular neck 9 for admitting air and gas to said casing. Above the casing 1 and directly over the wall 4 of the top thereof, is arranged an elongated cylindrical gas generating chamber 10, which has a closed rear end 11 and a threaded open end 12. This gas generating chamber passes through and is supported in openings in the plates 5 and

6, and near its rear end beyond the plate 5, its lower side is provided with a recess 13 for receiving the upwardly curved end 14 of a tube 15, which is constructed of comparatively thin material for becoming quickly heated. Said end of the tube is open and extends to the top of the gas generating chamber 10. The tube 15 extends along the underside of said gas generating chamber, and its forward end 16 passes through an opening in the front plate 6. Said forward end of the tube 15 curves downwardly and is provided with a rearwardly extending nozzle 17 directly opposite the tubular neck 9. The nozzle 17 is provided with a flared or conical outlet 18. A removable cap-screw 19 is threaded into the forward end of the tube 15 for closing the same, and also to provide a convenient means for the insertion of a wire or the like for easily cleaning the tube. The forward threaded end 12 of the gas generating chamber 10 is screwed into a cap 20, having a flange 21, which is fixed to the front end plate 6 by bolts 22. The cap 20 is provided with a central aperture 23, and is threaded in alignment therewith at 24 for the attachment of a feed pipe 25 leading from an elevated supply reservoir of kerosene or other similar liquid fuel. A shut-off valve 26 is arranged in the feed pipe 25 for controlling the flow of the liquid fuel to the casing 10. For obtaining a steady and even flow or distribution of the liquid fuel as it enters and passes through the casing 10, a core of suitable absorbent material 27 such as asbestos is arranged therein as indicated by 28.

In operation, one or more burners are arranged in a heating furnace, under a boiler, or other similar place in the usual manner, and the feed pipe connected to a supply reservoir of liquid fuel such as kerosene or other of the heavier oils. The supply reservoir is placed at a suitable distance above the burners, so that the liquid fuel will flow thereto by gravity. As the fuel enters the gas generating chamber 10, the core of absorbent material 27 arranged therein becomes saturated for its entire length. In order to light the burner, a torch or other heat giving means is applied for heating the gas generating chamber 10 sufficiently to transform the liquid fuel held by the core of asbestos into gas. The gas thus generated passes through the tube 15 and escapes

at the nozzle 17 with great force. As the gas leaves the nozzle, it spreads outwardly in all directions due to the conical outlet 18, and becomes mixed with air before entering 5 the tubular neck 9 and passing into the casing 1. The flow of the mixture, on account of the conical outlet of the nozzle, strikes the wall of the neck 9 as indicated by the dotted lines, thereby producing compression action 10 similar to an injector. Upon escaping through the slots 3 in the top of the casing, the mixture becomes ignited by the torch. After being lighted, the flame keeps the gas 15 generating chamber heated, and the burner continues to operate. The flame also heats the outer wall of the tube 15 and thereby causes the gas passing therethrough to become super-heated for obtaining greater expansion of the gas, and consequently higher 20 velocity of the flow thereof. This produces perfect combustion and a blue flame without the need of air pressure.

A burner constructed as illustrated and described, will operate efficiently for using 25 kerosene or other similar oils as fuel without the need of air pressure, thereby saving the expense of air pressure or forced draft; complete combustion is obtained, thus it is economical in the use of fuel; and on account of its simple construction, it is inexpensive to manufacture and easy to keep 30 clean.

Having fully described my invention, what I claim is:

35 1. In a liquid fuel burner, the combination of a casing, the casing having a perforated top wall, the casing being provided with an opening in its end, a chamber arranged above the top of the casing, means for supplying liquid fuel to the chamber, a tube 40 leading from the chamber, the tube extending along the under side of said chamber

and above the top of said casing, and the tube having an outlet opposite said opening of the casing, substantially as described. 45

2. In a liquid fuel burner, the combination of an elongated casing, the top of the casing being perforated, the casing being provided with an opening in its end, a tubular neck extending from the opening of the casing, a 50 gas generating chamber arranged longitudinally above the top of the casing, means for supplying liquid fuel to one end of the chamber, a tube connected at an acute angle to the other end of the chamber and extending parallel to and touching said chamber, the free end of the tube being bent downwardly, a nozzle projecting from the tube opposite said tubular neck, and a removable cap-screw closing the free end of the tube, 55 substantially as described. 60

3. In a liquid fuel burner, the combination of an elongated semi-circular casing, the flat side of the casing forming a top, the top of the casing being perforated, the casing 65 being provided with an opening in its end, a tubular neck extending from the opening of the casing, a gas generating chamber arranged longitudinally above the top of the casing, a core of absorbent material arranged 70 within said chamber, a tube leading from the upper part of said chamber, the tube extending along the underside of said chamber and above the top of the casing, the free end of the tube being bent downwardly, a 75 nozzle projecting from the tube opposite said tubular neck, the nozzle having a conical outlet for directing gas against the inner walls of said tubular neck, and a removable cap-screw closing the free end of said tube, 80 substantially as described.

In testimony whereof I affix my signature.

HERBERT FORESTER.
